UNITED STATES PATENT OFFICE.

FREDERICK A. PRESTON, OF HIGHLAND PARK, ILLINOIS, ASSIGNOR TO THE P. & M. COMPANY, OF CHICAGO, ILLINOIS, A CORPORATION OF ILLINOIS.

ANTICREEPER TIE-PLATE.

Application filed January 21, 1921, Serial No. 438,952.

To all whom it may concern:

Be it known that I, FREDERICK A. PRESTON, a citizen of the United States of America, residing at Highland Park, in the 5 county of Lake and State of Illinois, have invented certain new and useful Improvements in Anticreeper Tie-Plates, of which the following is a specification.

My invention relates to an anticreeper tie 10 plate.

It is common practice in the construction and maintenance of railways to provide metal plates on the ties underneath the rails, particularly when soft wood ties are 15 used, in order to provide a seat for the rails which plates protect the ties from unnecessary wear and serve to prevent turning movement of the rails about their longitudinal axes with the consequent liability to 20 cause train derailments and the cutting of the ties by the rail base flanges. It is also common practice to provide anticreeping devices to prevent longitudinal creeping of the rails on the ties. The anticreeping devices 25 are embodied in structures separate and distinct from the ordinary tie plates and add considerable to the cost of track equipment and maintenance. The primary object of my invention is to provide an im- 30 proved combination anticreeper and tie plate which is of simple construction and efficient in operation or use.

Some attempts have been made to provide a device of this general type in which 35 a jaw is provided adjacent one end of a tie plate of ordinary width and a spike opening at the other end, the jaw being arranged so as to grip one of the base flanges of the rail when a spike is driven through said 40 opening into the tie. The passing of a train over the track results in the rails being subjected to a wave-like motion, the effect of which is to tilt each tie plate upwardly in the direction of movement of the train as 45 the wheels approach the tie, and to tilt the tie plates in the opposite direction as the wheels pass over and beyond the tie. This up-and-down tilting or rocking movement of the tie plate causes unnecessary wear on 50 the bottom of the rail base and also causes the edges of the tie plate to cut into the face of the tie considerably bruising and damaging it. This tilting action of the tie plate also results in loosening the spikes in 55 the tie, chafing and wearing away the spikes

and in enlarging the spike openings. If a tie plate of ordinary width is anchored to the tie in a manner to obviate said tilting or rocking movement the disadvantages above noted are to a considerable extent 60 overcome, but in that case the wave-like motion of the rail tends to spring the jaw of the plate to such an extent that it no longer securely grips the rail base flange. Consequently such a tie plate is ineffective 65 as an anticreeping device. A more specific object of my invention is to provide a tie plate consisting of two relatively narrow independent members which are adapted to be placed side by side on the tie to provide 70 a seat for the rail, each member adjacent one end having a gripping jaw formed integrally therewith and adapted to fit over one base flange of the rail, said members being arranged so that said jaws, respec- 75 tively, engage the opposite rail base flanges, each member adjacent the other end having a spike opening which extends partially beneath the rail base so that when a spike is driven therethrough the member is 80 moved transversely with respect to the rail base and the jaw is forced into effective holding engagement with the adjacent flange.

The invention consists in the novel and 85 improved constructions, arrangements and devices to be hereinafter described and claimed for carrying out the above stated objects and such other incidental objects as will appear from the following descrip- 90 tion of a preferred embodiment of the invention illustrated in the accompanying drawings, in which—

Fig. 1 is a plan view of a device embodying the principles of my invention, 95

Fig. 2 is a sectional view taken on the line 2—2 of Fig. 1 showing the approximate position of the device relative to the rail base just prior to driving a spike through the spike opening provided in the device 100 opposite the gripping jaw, and

Fig. 3 is a view similar to Fig. 2 showing the position of the device relative to the rail base after the spike has been driven home.

Like characters of reference designate like parts in the several views.

Referring to the drawings it will be seen that the combination anticreeper and tie plate shown therein comprises a pair of rel- 110

atively narrow members 5, 5 placed side by side a short distance apart on the tie underneath the rail 6 longitudinally with respect to the tie 7 but transversely with respect to the rail. The members 5, 5 are each formed from a plate by rolling and provided adjacent one end with an overhanging jaw 8 which is adapted to fit over one of the rail base flanges. The members 5, 5 are arranged so that the respective jaws 8, 8 thereof engage the opposite rail base flanges. The jaws 8, 8 are each formed or shaped so that the angularity of the bearing surface 8^a thereof, before the member is in operative position under the rail base, is less than that of the top surface of the rail base flange with which it comes into contact when the member is in operative position under the rail base, consequently said jaws have to be forced open or sprung slightly upwardly when the members are in operative position under the rail base.

The members 5, 5 are each provided in the end opposite the jaw 8 with a spike opening 9 which is located with respect to the jaw 8 and the width of the rail base, so as to extend partially under the rail base when the plate is about to be placed in operative position thereunder as shown in Fig. 2. A spike 10 is then driven through the opening 9 into the tie which forces the tie plate transversely toward the spike 10 and which results in the jaw 8 being forced into effective holding engagement with the adjacent rail base flange, as shown in Fig. 3. The members 5, 5 are, preferably, each provided with a spike opening 11 adjacent the jaw 8 for the insertion of a spike 12 to secure that end of the plate to the tie. The opening 11 is located far enough away from the jaw so that when the spike 12 is driven home there will be no tendency to spring the jaw open and thereby loosen or weaken its hold upon the rail base flange.

45 A plurality of stiffening ribs 13 of any desired shape are preferably provided on the bottom side of the plates to prevent displacement of them on the tie.

The shape of the jaw 8 and the location of the spike opening 9, with respect to the jaw 8 and the width of the rail, result in the plate being firmly anchored to the rail base when the spike 10 is driven into the tie. The spikes 10 and 12 firmly anchor the plate to the tie. With a combination anticreeper and tie plate constructed according to my invention the rails are held at each tie against creepage in either direction. The two tie plates being relatively narrow in width and independent of each other, are not subjected to up-and-down or rocking movements, at least to any appreciable extent, when the rolling stock passes over the rails. The respective jaws of the tie plates are not pried up when the rolling

stock passes over the rails, as is the case when relatively wide tie plates are used, and they do not, therefore, lose their grip on the rail base flanges.

I claim:

1. An anticreeper tie plate comprising two relatively narrow independent members, each member having a base portion providing a seat for a rail and a rail gripping jaw which fits over one of the base flanges of the rail and is moved to its rail gripping position by forcibly moving said member transversely of the rail, said members being arranged so that their jaws, respectively, engage opposite base flanges of the rail, the base portions being adapted to be supported in a horizontal plane during the application of said members to a rail, and the bearing surfaces of said jaws being formed with less angularity than the top surface of the rail base flange, whereby said jaws are subjected to their greatest distortion when the members are in their applied position. 70 75 80 85

2. An anticreeper tie plate comprising two relatively narrow independent members, each 90

member having a base portion providing a seat for a rail and a rail gripping jaw formed integrally therewith, adapted to be distorted to fit over one of the base flanges of the rail and being moved to its rail gripping position by forcibly moving said member transversely of the rail, said members being arranged so that said jaws, respectively, engage the opposite base flanges of the rail, the base portions being adapted to 95 100 105 be supported in a horizontal plane during the application of said members, and the bearing surfaces of said jaws being formed with less angularity than the top surface of the rail base flange, whereby said jaws are subjected to their greatest distortion when the members are in their applied positions, each member having in the end opposite its said jaw a spiked opening which extends partially beneath the rail base so that when 110 a spike is driven therethrough the member is moved transversely with respect to the rail base and said jaw is forced into holding engagement with the adjacent flange. 115

3. An anticreeper tie plate comprising two 115

relatively narrow independent members, each member having a base portion providing a seat for a rail and a rail gripping jaw formed integrally therewith, adapted to be distorted to fit over one of the base flanges 120 of the rail and being moved to its rail gripping position by forcibly moving said member transversely of the rail, said members being arranged so that said jaws, respectively, engage the opposite base flanges of the rail, the base portions being adapted to be supported in a horizontal plane during the application of the members, and the bearing surfaces of said jaws being formed with less angularity than the top surfaces 125 130

of the rail base flanges, whereby said jaws are subjected to their greatest distortion when said members are in their applied position, each member having in the end opposite its said jaw a spike opening which extends partially beneath the rail base so that when a spike is driven therethrough the member is moved transversely with respect

to the rail base and said jaw is moved into holding engagement with the adjacent 10 flange, each of said members having adjacent its said jaw an opening for the insertion of a spike to secure that end of the member to the tie.

FREDERICK A. PRESTON.
